(57) **CLAIM**

The ornamental design for an air freshener device, as shown and described.

DESCRIPTION

The file of this patent contains at least one drawing executed in color. Copies of this patent with color drawings will be

provided by the Office upon request and payment of the necessary fee.

FIG. 1 is a perspective view of a first embodiment of an air freshener device, showing a black-and-white line drawing thereof;

FIG. 2 is a front elevational view thereof;

FIG. 3 is a side elevational view thereof;

FIG. 4 is a bottom plan view thereof;

FIG. 5 is a perspective view of a second embodiment of an air freshener device, showing a colored line drawing depicting a colorless top part and a green colored bottom part thereof;

FIG. 6 is a front elevational view thereof;

FIG. 7 is a side elevational view thereof;

FIG. 8 is a bottom plan view thereof;

FIG. 9 is a perspective view of a third embodiment of an air freshener device, showing a colored line drawing depicting a yellow colored top part and a green colored bottom part thereof;

FIG. 10 is a front elevational view thereof;

FIG. 11 is a side elevational view thereof;

FIG. 12 is a bottom plan view thereof;

FIG. 13 is a perspective view of a fourth embodiment of an air freshener device, showing a colored line drawing depicting a grey colored top part and a green colored bottom part thereof;

FIG. 14 is a front elevational view thereof;

FIG. 15 is a side elevational view thereof; and,

FIG. 16 is a bottom plan view thereof.
